DESIGN FOR A MOTOR DRIVEN CENTRIFUGAL PUMP

William C. Heath, Shorewood, Wis.

Application March 24, 1941, Serial No. 99,821

Term of patent 14 years

To all whom it may concern:

Be it known that I, William C. Heath, a citizen of the United States, residing in the village of Shorewood, in the county of Milwaukee and State of Wisconsin, have invented a new, original, and ornamental Design for a Motor Driven Centrifugal Pump, of which the following is a specification, reference being had to the accompanying drawing, forming part thereof.

The figure is a side perspective view of a motor driven centrifugal pump showing my new design. The other side of the pump is substantially the same.

I claim:

The ornamental design for a motor driven centrifugal pump, substantially as shown and described.

WILLIAM C. HEATH.
